[57] CLAIM

The ornamental design for a ski-rack, as shown and described.

DESCRIPTION

FIG. 1 is a bottom, front, and left side perspective view of a ski-rack showing my new design; and,

FIG. 2 is an enlarged left side elevational view thereof, the right side being a mirror image, and the top and rear surfaces being plain and unornamented.

1 Claim, 2 Drawing Sheets

FIG. 1
